UNITED STATES PATENT OFFICE.

WATERBURY LAWRENCE, OF WHITE PLAINS, NEW YORK.

INTERNAL-COMBUSTION ENGINE.

Application filed June 11, 1923. Serial No. 644,767.

To all whom it may concern:

Be it known that I, WATERBURY LAWRENCE, a citizen of the United States, and a resident of White Plains, in the county of Westchester and State of New York, have invented a new and Improved Internal-Combustion Engine, of which the following is a full, clear, and exact description.

This invention relates to internal combustion engines and particularly to an improved valve structure and has for an object to provide an engine in which a rotary valve is provided for each cylinder presenting a maximum opening for both the intake and exhaust.

Another object of the invention is to provide a rotary valve structure for an internal combustion engine in which a conically-shaped valve is used and held in place in such a manner as to readily operate at all times but permit any desired expansion or contraction without producing a binding action.

An additional object is to provide in an internal combustion engine a rotary valve structure which will remain open at the intake and exhaust strokes for substantially the full stroke of the piston.

A further object is to provide a structure wherein the valve will hold a maximum compression during the life of the engine without independent grinding or manual adjustment.

In the accompanying drawing—

Figure 1 is a longitudinal vertical section through an engine with a valve structure disclosing an embodiment of the invention.

Figure 2 is a side view of the valve member shown in Figure 1.

Figures 3, 4, 5 and 6 disclose diagrams illustrating the various positions of the various ports during one revolution of the valve member shown in Figure 2.

Figure 7 is a fragmentary sectional view disclosing a modified form of engine cylinder to that illustrated in Figure 1.

Figure 8 is a fragmentary sectional view through the valve stem supporting means shown in Figure 1.

Referring to the accompanying drawing by numerals, 1 indicates the usual crank casing which is associated with a cylinder 2, said cylinder being provided with a cylinder head 3, which head has been shown integral though if desired, it could be made separate and bolted to the cylinder 2 in

any desired manner. The head 3 for each cylinder tapers upwardly and merges into a tubular outlet 4 accommodating the stem 5 of the valve member 6, which valve member is cone-shaped and open at the bottom. A single port 7 is arranged in the valve member 6 and preferably extends from near the top to near the bottom. The stem 5 is provided preferably with a squared part 8 and a squared part 9 accommodating the squared parts of sleeve 22, which sleeve contacts with bearing members 10 and 11 mounted in suitable extensions 12 and 13 projecting from the bracket or frame 14 which is secured in any desired manner to the head 3. The extension 12 also carries a rotatable shaft 15 connected at one end with the sprocket wheel 16, which sprocket wheel accommodates the chain 17, said chain extending downwardly and over the sprocket wheel 18 secured to the crank shaft 19. The shaft 15 carries a worm 20 for each cylinder, there being only one cylinder and associated parts shown but it will be evident that any desired number might be used without departing from the spirit of the invention.

The worm 20 continually meshes with the worm gear 21 rigidly secured by a key 21' or may be formed integral with the sleeve 22. This sleeve, as shown in Figure 8, is formed with a squared portion at the top and bottom for engaging the squared portions 8 and 9 of the stem 5 with a sliding fit. The sleeve 22 is formed with a slot 23 through which pin 24 extends, said pin being fixed rigidly in the stem 5. This pin acts as a stop for the spring 25, which spring continually acts against the hub 24' of the gear wheel 21 and against the pin 24 and thereby tends to move the valve upwardly and hold it tightly to its seat while permitting a free rotation thereof. The reciprocal movement of the stem 5 is very small as this movement is permitted merely to take care of the expansion and contraction of the valve member 6 as it operates.

The head 3 which receives the valve member 6 is provided with an intake port 26 and an exhaust port 27. Both of these ports coact with the port 7 of the valve member 6 during the operation of the engine. In Figures 3 to 6 inclusive, diagrams have been shown illustrating the position of the ports at the end of the respective strokes. In Figure 3, the ports are shown at the end of

the intake stroke, Figure 4 at the end of the compression stroke, Figure 5 at the end of the explosion stroke and Figure 6 at the end of the scavenging stroke. From an examination of these diagrams, it will be seen that the ports are of maximum size and, consequently, remain open for a maximum time in order to secure the proper intake and exhaust. The single port 7 of the valve member 6 readily permits the gas to be drawn in at the intake stroke and also readily permits the burnt gases to be exhausted as well as permits the spark plug 28 to function at the proper time. This spark plug is preferably positioned approximately 120° from the center of the intake port 26 so that it will be uncovered at the proper time to ignite the compressed gases. The port 7 is sufficiently wide to permit the spark to be advanced or retarded in the usual manner. The timing of the valve is controlled by the location and width of the ports in the valve and the cylinder head. It is also evident that the valve may be lubricated by oil holes and grooves or in any other desired manner whereby there will be an efficient operation of the respective parts. It is also evident that the position of the spark plug can be varied to accommodate the arrangement of the ignition timing.

In Figure 7 a slightly modified construction is disclosed in which a by-pass or side

opening 29 is provided in the head 3 which accommodates the plug 28'. This arrangement of spark plug is desirable where a spark is to be advanced or retarded greatly, though ordinarily the arrangement disclosed in Figures 3 to 6 is preferable.

What I claim is:—

In an internal combustion engine, a cylinder provided with a head having a cone-shaped compression chamber, said head being formed with intake and exhaust ports with their centers approximately ninety degrees apart, a cone-shaped valve member fitted into said compression chamber and provided with a single port coacting with said intake and exhaust ports, a stem extending from said valve member to a point exteriorly of the cylinder, a sleeve loosely mounted on said stem, said sleeve having a slot at one point, a pin extending through said slot, a spring acting on said pin for urging the same in such a direction as to maintain said valve seated, said stem being formed with squared portions and said sleeve being formed with a square bore fitting said squared portions, means for driving said sleeve whereby said valve will be rotated, and a spark plug carried by said head approximately half way between the intake and exhaust ports.

WATERBURY LAWRENCE.
